UNITED STATES PATENT OFFICE.

CHARLES A. MOORE, OF ST. PAUL, MINNESOTA.

AIR-CIRCULATING APPARATUS FOR CARS.

1,344,057.

Specification of Letters Patent. Patented June 22, 1920.

Application filed April 4, 1914, Serial No. 829,509. Renewed November 7, 1919. Serial No. 336,473.

To all whom it may concern:

Be it known that I, CHARLES A. MOORE, a citizen of the United States, residing at St. Paul, in the county of Ramsey and State of Minnesota, have invented a new and useful Improvement in Air-Circulating Apparatus for Cars, of which the following is a specification.

This invention relates to an improved air 10 circulating apparatus for cars, or other body structures forming provision chambers, and has for its primary object the production of improved apparatus for more efficiently circulating the air in a car or other structure 15 whereby perishable lading is more perfectly preserved. My improved apparatus is adapted to more efficiently circulate the air in a car or other structure than heretofore when it is being cooled or heated, or when 20 the cooling or heating apparatus is not employed.

In the accompanying drawings forming 25 part of this specification, Figure 1 is a plan partly broken away and in section of my invention, the sectional portion being taken on the line X—X of Fig. 2; Fig. 2 is a section taken on the line Y—Y of Fig. 1; Fig. 3 is a similar view to Fig. 2 for the purpose of illustrating the circulation of 30 air when the heater is in operation and Figs. 4 and 5 are longitudinal vertical sections taken on the line Z—Z of Fig. 3.

In the drawings A indicates a car body or other suitable structure having insulated end 35 walls 2 and 3, insulated side walls 4 and 5, insulated floor 6, and insulated ceiling 7. Spaced from the inner surfaces of the side and end walls, ceiling and floor is an inner casing 8 forming air passages 9 for the circulation of air throughout the entire interior 40 of the lading chamber B in the car. That portion of the inner casing lying adjacent the floor is provided with slats 10 spaced apart for permitting air to circulate either 45 up or down through the floor.

Located in the top of the car adjacent the ceiling is an overhead ice bunker C, the ends 50 of which are remote from the ends of the car and the floor positioned above the doorways 12. The ends of the ice bunker terminate a short distance below the roof of the car to produce passages 13 between the ice bunker and the lading chamber. Immediately above the ends of the ice bunker the 55 air passages 9 in the roof of the car open into the ice bunker to form a communication

between the ice bunker and the lower portion of the lading chamber through the walls of the car. The ends of the ice bunker have double walls spaced apart and the floor of 60 said bunker is formed with a drip pan 14, which is connected to drain pipes 15 leading down through the side walls 4 and 5 of the car, which open into traps 16 below the floor of the car. The space between the 65 end walls and between the drip pan and floor of the ice bunker form a communication for air to circulate from the top of the car down through the end walls and floor of the bunker and drip pans into the bottom 70 portion of the lading chamber, openings 17 being provided near the floor of the car into the drain pipes and into the passage 9 in the floor of the car. The floor of the ice bunker is conveniently sloped endwise 75 and crosswise for draining water from the bunker, it being understood that drain pipes such as 15 are disposed in both side walls 4 and 5 of the car. Suitable hatchways 18 are provided in the roof remote from the 80 ends of the car and leading into the ice bunker for filling it with ice.

Disposed in the car below one side of the ice bunker and immediately adjacent the side wall 5 is a heater, which as illustrated 85 consists of a stove D standing on the floor of the car. This stove which may be of any suitable construction is accessible through a doorway 19 in the wall 5 from outside of the car, although it is not necessary to employ the doorway 19, because it is obvious the door of the stove can be made accessible from inside of the car when desired. The stove is shown provided with the usual chimney or stove pipe 20 for smoke and gases 90 passing to the outside atmosphere through the roof of the car. The stove and stove pipe are enveloped by a jacket 21 spaced from the walls of the stove and the stove pipe, and terminating at its upper end a short 100 distance below the roof of the car, but connected near the floor with a passage 22 communicating with the outer atmosphere. The doorway and ash door having the usual draft damper project through the casing or 105 jacket 21 and are accessible through the doorway 19, there being a draft passage 19' in the door closing said doorway. Around the jacket 21 there is an outside guard casing 23, which is spaced from the jacket to 110 protect the jacket and at the same time forming an air circulating chamber, the

upper end of the jacket being spaced from the roof and floor of the car to form air communications with the lading chamber. The upper end of the guard casing 23 projects above the floor of the ice bunker to prevent water flowing down from the bunker into the lading chamber and the space at the upper end of said guard is surrounded by a screen 24 to prevent ice coming into contact with the jacket. The spaces at the ends of the ice bunker are also covered by screens 25 to prevent ice from spilling over into the lading chamber. Placed within the guard and connected with the upper portion of the smoke pipe is a branch pipe 26 through which vitiated air is adapted to be conducted from near the floor of the car through the space between the lower end of the guard and the floor and from the passage 9 in the floor.

A vertical air flue 27 is also constructed in the guard casing 23 which forms a communication for the circulation of air between the upper and lower ends of the lading chamber indicated by the arrows in Figs. 2 and 5, to-wit:-

Fresh air is drawn down through the smoke pipe 20 and branch 26 into the lower portion of the car. This fresh air from the outside circulates throughout the lading chamber and through the passage 9 up over the ends of the bunker into contact with the ice. Part of the chilled air passes downward to the outside atmosphere through jacket 21 and floor opening 22, and part of said air returns through the flue 27, the passages in the walls and floor of the bunker and the drain pipes 15, into the lower portion of the lading chamber. This circulation of air continues while there is any ice in the bunker, part of the air being deflected into the upper end of the jacket 21 and passage 22 of the floor of the car and conducted to the outside atmosphere. In this manner there is produced throughout the lading chamber in the car a circulation of pure cold air beneficial to preserving the lading of perishable goods.

When the car is used in winter time and it is desired to heat the lading chamber to prevent freezing of the lading, the stove D is operated in the usual manner. When it is a coal stove, coal is placed therein and oxygen supplied through the doorway 18. It is obvious however that the stove may be replaced by an oil or gas heater when desired, and that it can be operated from inside instead of outside of the car. Fresh air is admitted through the passage 22 in the floor of the car as illustrated in Figs. 3 and 4 and warmed by the stove and passes upwardly into the top of the lading chamber through the jacket 21. This pure warm air circulates through the passage 9 in the upper walls of the car and over the ends of the ice

bunker downward through the lading chamber and lading chamber walls. Part of this air keeps circulating, passing upwardly through the drains 15 and air flue 27, while cold vitiated air is carried off through the passage 9 in the floor, branch 26 and smoke pipe 20 with the smoke and gases to the outside atmosphere. As a result pure warm air is circulated freely throughout the entire leading chamber, vitiated air passing downward through the slatted floor of the car and to the outside atmosphere. When the ice bunker and heater are not operated the smoke pipe and passage 21 provide ingress and egress openings causing a circulation of air similar to that produced when the car is either heated or cooled as described only to a less degree, but sufficient to provide a circulation of pure air through the lading chamber to preserve various kinds of perishable goods.

In accordance with the patent statutes I have described the principles of operation of my invention together with the apparatus which I now consider to represent the best embodiment thereof, but I desire to have it understood that the construction shown is only illustrative and that the invention can be carried out by other means and applied to uses other than those above set forth within the scope of the following claims.

Having described my invention, what I claim as new and desire to protect by Letters Patent is:-

1. A body structure forming a provision chamber, a draft duct forming a communication between the outside atmosphere near the upper portion of said body structure and the lower portion of said chamber, and a second draft duct forming a communication between the outside atmosphere near the lower portion of said body structure and the upper portion of said chamber; whereby pure outside air is positively circulated in either upward or downward direction completely through said chamber when said ducts are influenced respectively either by a heating or cooling medium.

2. A body structure forming a provision chamber, a draft duct forming a communication between the outside atmosphere near the upper portion of said body structure and the lower portion of said chamber, and a second duct forming a communication between the upper portion of said chamber and the outside atmosphere near the lower part of said body structure, said ducts being inclosed one within the other, whereby heat radiating from the walls of said ducts is adapted to promote circulation of air through said ducts and throughout said chamber.

3. A body structure forming a provision chamber, a duct forming a communication

between the outside atmosphere near the upper portion of said body structure and the lower portion of said chamber, a second duct surrounding said first duct and forming a communication between the upper portion of said chamber and the outside atmosphere near the lower portion of said body, and a third duct adjacent to said first and second ducts forming a direct communication between the upper and lower portions of said chamber; said first and second ducts being adapted to circulate air from the outside atmosphere between the

upper and lower portions of said chamber and expel vitiated air from said chamber 15 and said third duct being adapted to complete a circuit for the local circulation of part of the air in said chamber.

In testimony whereof I have signed my name to this specification in the presence of 20 two subscribing witnesses.

CHARLES A. MOORE.
